UNITED STATES PATENT OFFICE.

NOTEN D. BALLANTINE, OF CHICAGO, ILLINOIS.

TEMPORARY HOLDER FOR CAR-REPORT BLANKS AND THE LIKE.

1,170,793.

Specification of Letters Patent.

Patented Feb. 8, 1916.

Application filed August 16, 1911. Serial No. 644,442.

To all whom it may concern:

Be it known that I, NOTEN D. BALLANTINE, a citizen of the United States, and a resident of Chicago, county of Cook, and

5 State of Illinois, have invented certain new and useful Improvements in Temporary Holders for Car-Report Blanks and the like, of which I do declare the following to be a full, clear, and exact description, reference being had to the accompanying drawing, forming part of this specification.

The present invention has for its object to provide a simple and effective means for temporarily holding blanks to be written upon, such, for example, as conductors' car reports, wheel reports or the like, and the invention consists in the features of improvement hereinafter described, illustrated in the accompanying drawing and particularly pointed out in the claim at the end of this specification.

Figure 1 is a perspective view of a temporary holder embodying my invention. Fig. 2 is a fractional view upon an enlarged 15 scale in cross-section. Fig. 3 is a fractional view upon an enlarged scale of two adjacent leaves connected by a bias fabric.

As shown, the holder comprises the front cover A and back cover A' hinged together 30 as at A³. Between the covers A and A' are arranged a series of intermediate hinged spacing boards, plates or leaves B. Preferably, each of the covers A and A' is formed of a cardboard body a to which is glued the 35 cloth a', the edges of this cloth being turned over the edges of the body a upon its inner face in the usual manner, and the central part of the cloth a' forms the hinge back A³ that unites the covers A and A'. In 40 order to enable the inner face of each of the covers A and A' to present a smooth and even support for the blank while it is being written upon, I attach, as by glue upon the inner face of each of the covers 45 A and A', a sheet of cardboard a² or like material sufficiently thick to afford a smooth support for the blank and avoid any irregularity incident to the folding over of the edges of the cloth a' upon the inner face 50 of the body a. That is to say, the sheet a² will be so thick that when it is attached to the body a of the cover and extends across the folded edges of the cloth a', the folds of the cloth do not form ridges around the 55 edges of the sheet a², but this sheet presents

a smooth surface over substantially the whole inner face of the cover, thereby enabling the blank to be written upon to its extreme edges.

The boards or sheets B are preferably 60 formed of at least two thicknesses of cardboard or like material, in order that the sheets B may present smooth and unbroken surfaces to support the blanks to be written upon from edge to edge. These sheets B have 65 their inner edges hinged to the holder in the following manner: A strip C of cotton cloth or other suitable material is connected to each of the covers A and A' by gluing the edges of this strip C between the facing sheet a² of 70 each cover and the body a of each cover, and the strip of cloth C is provided with a number of folds c which are arranged between the thicknesses of the cardboard or like material of which the portions or sheets 75 B are formed. These folds c of the cloth C are firmly glued in place and as the cloth is very thin, the folds c of the cloth do not form any appreciable irregularity in the surfaces of the sheets or boards B. Ob- 80 viously, any desired number of sheets or boards B may be employed, but these sheets or portions should be sufficiently thick or heavy to afford smooth surfaces for the blanks while being written upon.

By reference more particularly to Fig. 3 of the drawing, it is seen that the cloth C is cut upon the bias so that both its warp and weft threads extend between and unite the sheets or boards B together and to the 90 covers A and A'. By thus disposing the cloth C so that the strength of both its warp and weft threads is utilized, greater durability is attained and I am enabled to use a lighter quality of cloth than would 95 otherwise be required. The report blanks will be temporarily held within my improved holder by placing a blank between the cover A and the facing sheet or leaf B and securing it thereto temporarily, as with 100 a wire paper clip or by an elastic band passing from end to end of the cover at its hinge joint; and similarly, blanks will be placed between the succeeding leaves or boards B. My invention affords an exceedingly simple 105 and effective temporary holder for report blanks, such, for example, as are used by conductors of railway trains, yard masters and others and it is adapted to sustain the report blanks, so that each blank can be 110

filled out or written upon to its extreme edge while supported upon a smooth surface.

Having thus described my invention what I claim as new and desire to secure by Letters Patent, is:—

A temporary holder for report blanks and the like comprising front and back covers formed of separate, outer, rigid boards, a common cloth covering extending over and secured to the outer faces of said outer boards and forming a flexible hinge between the same, the edges of said covering being folded over and secured to the inner faces of said outer boards, inner boards of heavy card board secured to the inner surfaces of

said outer boards and extending over the folded edges of the cloth covering, a leaf of the same size as said inner boards comprising two thicknesses of heavy card board secured together, and a flexible fabric strip having its ends extending between and secured to the inner and outer boards of said cover and having a fold extending between and secured to the boards of said leaf, said inner boards and said leaf having smooth, uninterrupted rigid surfaces for supporting the blanks, substantially as described. 20 25

NOTEN D. BALLANTINE.
